Attorney.

UNITED STATES PATENT OFFICE.

CHARLES A. KALINA, OF EXETER, NEBRASKA.

ROAD SCRAPER AND SNOWPLOW.

Application filed July 17, 1925. Serial No. 44,318.

To all whom it may concern:

Be it known that I, CHARLES A. KALINA, a citizen of United States, residing at Exeter, in the county of Fillmore and State of 5 Nebraska, have invented certain new and useful Improvements in Road Scrapers and Snowplows, of which the following is a specification, reference being had therein to the accompanying drawing.

10 The present invention relates to road scrapers and snow plows, and aims to provide a novel and improved device of that kind which is attachable to a tractor, motor truck or other motor-propelled vehicle to be 15 used for scraping a dirt road, or to be used as a snow plow.

Another object of the invention is the provision of novel means for connecting the 20 scraper blade with the vehicle, and novel 25 means for adjustably supporting said blade from the road.

A further object is the provision of such 25 a device having novel means whereby the scraper blade may be adjusted conveniently 30 from the vehicle to which the device is attached.

With the foregoing and other objects in 35 view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein—

Figure 1 is a plan view of the device as 40 attached to the front axle of a motor-propelled vehicle.

Fig. 2 is a side elevation, partly in section on the line 2—2 of Fig. 1 and other portions being shown in section.

Fig. 3 is a cross section on the line 3—3 45 of Fig. 2.

The scraper blade 7 is disposed obliquely in front of the tractor, motor truck, or other motor vehicle, and is connected to the forward ends of pusher beams 8. Thus, plates 50 9 are secured to the back side of the blade 7 and have rearwardly extending vertical flanges 10 through which pivot pins 11 extend, and said pins engage through forward

terminals of the beams 8, to pivotally connect the blade with said beams.

In order to brace the blade 7, posts 12 are secured on the beams 8 near the forward ends thereof, and brace rods 13 have angularly extending terminals engaging through the posts 12 and flanges 10 of the 60 plates or members 9. Cotter pins 14 or other retaining elements are engaged in the terminals of the brace rods 13 to hold them in place. The rods 13 are shown as located above the forward ends of the beams 8, and those flanges 10 of the plates 9 which are engaged by the rods 13 have apertures 15 at their upper and lower ends above and below, respectively, the horizontal plane of the beams 8 and pivots 11, in order that the 70 blade 7 may be used in inverted positions, as hereinafter referred to. The pivots 11 may fit loosely in slots in the forward terminals of the beams 8 to permit of slight vertical movement of the blade 7 relatively to 75 said beams, in order that the lower edge of the scraper blade may pass over unyielding obstructions. It will be noted that the brace rods 13 extend forwardly and downwardly from the posts 12 to their forward terminals 80 which engage the flanges 10, so that when the blade moves upwardly it is swung so that its upper edge moves forwardly and its rear edge moves rearwardly, thereby tilting the blade forwardly so that it will more 85 easily pass over the obstructions. The blade will normally gravitate to its lowermost position.

The rear terminals of the beams 8 are pivoted as at 16, to supporting bars 17 that are 90 secured to and project forwardly from the front axle A of the vehicle, the beams 8 being bifurcated to receive the bars 17. The rear terminals of said bars are offset, as at 18, to engage over the axle A, and pieces 19 have 95 complementing offset portions 20 also engaging the axle to provide clamps for attaching said bars 17 to the axle. The pieces 19 are secured to the bars 17 by means of bolts 21 in order that the device may be 100 readily attached to and detached from the vehicle. The rear ends of the beams 8 have stops 22 to engage the bars 17 in rear of the pivots 16, so as to limit the downward swinging movement of the beams 8, but permitting 105 said beams to swing upwardly. The

pivots 16 are in transverse alinement in order that the beams 8 can be swung upwardly and downwardly about the transverse axis of the pivots 16, for raising and lowering the 5 blade 7.

In order to adjustably support the beams 8 and blade 7 from the road, vertical standards 23 are slidable in the beams 8 immediately behind the posts 12, and caster forks 10 24 are swivelled to the lower ends of said standards below the beams 8 and have rollers 25 therein to roll on the surface of the road. Said casters, comprising the forks 24 and 15 rollers or wheels 25, trail from the lower ends of the standards 23, and are capable of turning about vertical axes when the vehicle is steered. Rearwardly extending plates 26 are secured to the posts 12 and overlap the standards 23 in order to assist in guiding 20 said standards and holding the parts assembled, and rollers 27 are mounted between the plates 26 behind the posts 12 to bear against the forward edges of the standards 23.

Adjusting means are provided for adjustably supporting the beams 8 from the standards 23. For this purpose, pedestals 28 are secured on the beams 8 behind the standards 23, and worm wheels 29 are mounted for rotation in said pedestals and mesh with rack 30 teeth 30 with which the standards 23 are provided at their rear edges. Shafts 31 are journaled in bearings 32 with which the pedestals 28 are provided above the worm wheels 29, and worms 33 are secured on the shafts 31 and mesh with the worm wheels. Thus, the rotation of the worms 33 will rotate the worm wheels 29, and said worm wheels engaging the rack teeth 30 of the standards 23 will cause the worm wheels to either climb 40 upwardly on the standards or to descend thereon, for raising or lowering the beams 8 and blade 7.

Operating shafts 34 extend rearwardly from the worm shafts 31, and are connected 45 at their forward ends by universal joints 35 with the shafts 31, in order that the shafts 34 may extend rearwardly at different angles to any convenient location on the vehicle. The shafts 34 have cranks 36 or other 50 suitable means at their rear ends for conveniently rotating said shafts, and bearings 37 may be provided on the vehicle in which the shafts 34 are journaled, in order to support said shafts from any suitable part of 55 the vehicle. Thus, the shafts 34 may be conveniently rotated by the operator or driver of the vehicle for adjusting the scraper blade upwardly or downwardly.

The beams 8 are of different lengths on 60 account of the blade 7 being disposed obliquely, as seen in Fig. 1. As shown in Fig. 1 the blade 7 will direct the dirt or snow to the left in the forward movement of the vehicle. However, the blade 7 may be 65 reversed. This is done by interchanging the

beams 8, and inverting the blade 7, the rods 13 having been detached. Said rods 13 may then be engaged with the opposite apertures 15, it being noted that when the blade 7 is inverted there will, in either position of the 70 blade, be apertures 15 in position to receive the rods 13.

The beams 8 are braced by an oblique brace rod 38 having an eye 39 at one end loosely engaging an eye 40 of a bolt 41 engaging the 75 longer beam 8, and said bolt may be one of the bolts which fasten the corresponding pedestal 28 to said longer beam. The rod 38 has a hook 42 at its opposite end to engage in an eye 43 secured to the shorter beam 8, and said eye 43 may be a part of an eye bolt constituting the pivot between the shorter beam 8 and the corresponding bar 17. When the beams 8 are interchanged to position the blade 7 in the reverse oblique 80 position, the eye bolts having the eyes 40 and 43 are reversed to position said eyes at the inner or adjacent sides of the beams, as will be apparent.

The device is quickly and conveniently 85 attached to the front axle of a motor vehicle so that the device is pushed by the vehicle, and the device may either be used as a road scraper or as a snow plow. In detaching the device, the bolts 16 may be removed 90 to detach the beams 8, leaving the bars 17 on the axle. The beams 8 may be swung upwardly, and are supported from the standards 23 which have the casters at their lower ends that travel on the road, in order 95 to support said beams and the scraper from the casters. 100

Having thus described the invention, what is claimed as new is:—

1. A device of the character described comprising a scraper blade, means for connecting said blade with a vehicle for the up and down movement of said blade, members having vertical sliding connection with said means and having portions to bear on the road, and adjusting means connecting said members and firstnamed means for raising and lowering the firstnamed means on said members. 105

2. A device of the character described comprising a scraper blade, means for connecting said blade with a vehicle for the up and down movement of said blade, standards slidably connected with said means, casters connected to the lower ends of said standards to move on the road, and adjusting means connecting said standards and firstnamed means to raise and lower said firstnamed means on the standards. 110

3. A device of the character described comprising a scraper blade, means for connecting said blade with a vehicle for the up and down movement of said blade, a worm wheel carried by said means, means connected to said firstnamed means and geared 115 120 125 130

to said worm wheel and having a portion to bear on the road for supporting the first-named means and blade, and a worm mounted on the firstnamed means and meshing with said worm wheel for turning the worm wheel to raise and lower the firstnamed means with reference to said portion.

5 4. A device of the character described comprising a scraper blade, beams connected to the blade for carrying same, means for hingedly connecting said beams with a vehicle, worm wheels mounted on the beams, members connected with the beams and having portions to bear on the road, said 10 beams being movable upwardly and downwardly with reference to said members, said members being geared to said wheels for raising and lowering said beams when said 15 wheels are rotated, and worms mounted on the beams and meshing with said wheels.

5 5. A device of the character described comprising a scraper blade, beams behind and secured to said blade for carrying the blade, means for hingedly connecting said 20 beams with a vehicle, standards slideable vertically in the beams, casters connected to the lower ends of the standards to move on the road, and adjusting means connecting said standards and beams to raise and 25 lower the beams.

6. A device of the character described comprising a scraper blade, beams behind

and connected to said blade to carry the blade, means for connecting said beams with a vehicle for the upward and downward movement of the beams, standards slideable vertically in the beams and having means at their lower ends to move on the road, worm wheels mounted on the beams, said standards having rack teeth engaging said 35 wheels, and worms mounted on the beams and engaging said worm wheels for turning the same to raise and lower said wheels and beams on the standards.

7. A device of the character described comprising supporting means, a scraper blade having a pivotal and sliding connection with said means permitting the blade to move upwardly and downwardly with reference to said means as the blade moves 40 over the road, and also permitting forward and rearward tilting movement of the blade, and inclined brace rods pivotally connected to said blade and means to brace the blade against such tilting movement when the 45 blade is in any of its vertical positions with reference to said means, said brace rods being arranged to tilt the blade forwardly when the blade is raised with reference to 50 said means.

55 In testimony whereof I hereunto affix my signature.

60 CHARLES A. KALINA.
